Primary Examiner — Jeffrey D Asch*Assistant Examiner* — Rebekah A Caruso(74) *Attorney, Agent, or Firm* — Westman, Champlin & Koehler, P.A.(57) **CLAIM**

The ornamental design for an audio recording/reproducing device, as shown and described.

DESCRIPTION

FIG. 1 is a front elevational view of the audio recording/reproducing device.

FIG. 2 is a rear elevational view of the audio recording/reproducing device.

FIG. 3 is a right side view of the audio recording/reproducing device.

FIG. 4 is a left side view of the audio recording/reproducing device.

FIG. 5 is a top plan view of the audio recording/reproducing device; and,

FIG. 6 is a bottom view of the audio recording/reproducing device.

In the drawings, the dash-dot-dash broken lines depict claim boundaries and form no part of the claim; the evenly spaced broken lines illustrate portions of the article that form no part of the claimed design.

1 Claim, 6 Drawing Sheets(56)
